UNITED STATES PATENT OFFICE

CARL FREDERICK MACK, OF PHILADELPHIA, PENNSYLVANIA, ASSIGNOR OF ONE-HALF
TO LEON EDELSON, OF PHILADELPHIA, PENNSYLVANIA

FABRIC GUIDING AND SEAMING MECHANISM

Application filed November 3, 1928. Serial No. 316,903.

The present invention relates to improvements in sewing machines of the cup-feed type and more particularly to an improved mechanism for supporting the fabric to be stitched in proper position with respect to the stitching head while it is being fed through the machine.

In the manufacture of knitted goods such as stockings where it is found desirable and necessary to stitch a seam longitudinally from top to bottom thereof, or vice versa, it has been the more or less usual practice to support and feed the fabric to be stitched through the machine in substantially a vertical plane by means of a pair of cup-shaped feed wheels rotating in opposite directions. In order to obtain a seam which is uniform in character, especially as respects neat appearance, it is necessary that it follow closely certain of the longitudinally extending wales of the fabric. Ordinarily, however, it is difficult in practice to so guide the fabric that the wales are not crossed during the stitching or overseaming operation with the result that the work is often spoiled in appearance. Another objectionable feature of the seaming operation as ordinarily performed is that the seam it produces is uniformly too heavy due primarily to the fact that the needle of the machine passes through the fabric at a point too far removed from the edge thereof, or in other words too many wales are taken up in the stitching or overseaming operation. Still another objectionable feature is the difficulty encountered during the seaming operation in maintaining the fabric in proper position such that the edges thereof which are to be overseamed lie constantly in the same horizontal plane, the tendency being for the fabric to drop as it is fed through the machine with the result that the needle either takes up less than the desired number of wales or else passes entirely over the edges of the fabric, thus spoiling the seam.

It is among the general objects of this invention to obviate and avoid the foregoing objectionable features and difficulties of manufacture by the provision of cooperating parts which effectually preclude any drop-

ping down of the fabric as it is being fed through the machine, these parts being relatively so arranged that the resultant seam is uniformly neat in appearance and substantially flat.

More specifically one of the objects of the invention is the provision of a horizontally disposed pressure member arranged for slidable movement in the needle guide, which member cooperates with the stitch finger member to maintain the fabric in proper stitching position.

A still further object is the provision of a pressure member arranged for sliding movement on the needle guide, together with resilient means tending constantly to urge the pressure member into engagement with the fabric as the latter is fed through the machine by the rotating feed cups.

Still another object of the invention is the provision of a stitch finger of a proportion calculated to produce a fine stitch in combination with a spring pressed pressure member operative to insure the constant proper positioning of the fabric whereby to secure a seam of minimum depth or thickness.

Still another object of the invention is the provision of a guiding and uncurling device arranged to one side of the cup feeding means and in the path of travel of the fabric to be seamed, this device including cooperating fabric engaging members each of which is provided with complementally formed means for effectually precluding any downward displacement of the fabric.

Other objects, and objects relating to details and economies of operation and manufacture, will appear more fully hereinafter. A preferred form of the invention is described in the accompanying description and illustrated in the drawings forming a part thereof. In these drawings:

Figure 1 is a perspective view of the needle and looper and their associated parts, including the rotatable cup feed and the devices for insuring maintenance of the fabric in proper position;

Figure 2 is a perspective view similar to Figure 1, but with the guiding and unfurl-

ing members omitted for the sake of clear-
ness;

Figure 3 is a side elevation of the guiding
and unfurling device;

Figure 4 is a view showing the fabric engag-
ing faces of the members constituting the de-
vice shown in Figure 3;

Figures 5, 6 and 7 are, respectively, top
plan, side elevation, and bottom plan views
10 of the stitch finger member and needle guide,
these parts being shown in operatively as-
sembled relation.

Figures 8 and 9 are front and side views,
respectively, of a modified form of guiding
15 and unfurling device; and

Figure 10 is a cross section taken on the
line 10—10 of Figure 9.

While the drawings show a particular type
of cup-feeding overseaming machine, it is
20 to be understood that the invention is adapted
for use with other types as well and that the
particular machine shown is for illustrative
purposes only. The overseaming machine,
designated generally by the reference nu-
25 meral 10, comprises the main frame 11 in
front of which are located a pair of cup-
shaped feed wheels 12 and 13 arranged for
simultaneous rotation in opposite directions
30 and in substantially the same horizontal
plane. These feed wheels are provided with
milled or serrated cooperating surfaces be-
tween which the material or fabric to be
stitched or seamed is clamped and fed through
35 the machine in substantially a vertical plane,
the upper edges of the fabric extending a
slight distance above the top plane of the feed
wheels.

The needle 14 of the stitch forming mech-
anism is carried by the needle bar 15, this bar
40 being mounted for horizontal reciprocable
movement such that the needle is caused to
move back and forth across the common tan-
gential plane and above the upper edges of
the feed wheels 12 and 13, with the result that
45 the needle will be caused to penetrate the
edges of the fabric extending above the feed
wheels. The mechanism for operating the
needle bar may be of the usual type and forms
no part of the present invention. Cooper-
50 ating with the needle 14 is a looper 16 suit-
ably supported by the looper rod 17, this
looper rod being arranged for horizontally
reciprocable, oscillatory and vertical move-
55 ments in the manner and for the purpose well
understood by those skilled in the art, the
construction of the looper and mechanism
for operating same forming no part of the
present invention.

Projecting forwardly from the front face
60 of the machine are a pair of thread guides 18
and 19, the needle thread (n. t.) being led
through the guide 18 and associated thread
controlling devices 21 to the eye of the needle
14, while the looper thread (l. t.) is led
65 through the guide 19 and associated thread

controlling devices 20 to the eyes of the looper
16. The looper 16 is provided with a thread
spreading member 22 projecting beneath the
looper eye, this member being adapted for
engagement with the needle thread as it passes
70 from the needle eye to the fabric to insure
proper entry of the needle into the looper
thread loop without interference by its own
thread.

Cooperating with the needle is the needle
guide member, designated generally by the
reference numeral 23, including a main plate
24 adapted to overlie the outer feed wheel 12.
This plate 24 is provided with a longitudi-
nally extending groove 25 for receiving the
80 point of the needle 14 as it passes through the
fabric and is further provided with a hook-
shaped member 26, the curved extremity of
which overlies the edge of the feed wheel 12
85 to prevent the seamed fabric from being
caught thereby. On the side of the needle
groove opposite the member 26 is a pressure
member 27, this pressure member being ar-
ranged for longitudinal movement on the
90 plate 24 toward the fabric as the latter passes
between the feed wheels 12 and 13. A spring
wire 28, having one end thereof fixed to the
plate 24, as at 29, is arranged with its oppo-
site end engaging the outer end of the pres-
95 sure member 27 whereby to provide an ef-
fective means for constantly urging the same
inwardly toward the fabric. An elongated
slot 30 is provided in the pressure member
100 and a screw 31 projects therethrough and into
the body of the plate 24, this slot and screw
cooperating to prevent either lateral or ver-
tical displacement of the pressure member
relative to its supporting plate 24. The in-
105 ner end of the pressure member is provided
with a lateral extension 32 constituting the
fabric engaging edge of the pressure mem-
ber, the lateral extremity of this extension be-
ing slightly curved in a direction away from
110 the vertical plane of the path of movement
of the fabric through the machine. While
in the present instance the plate 24 is shown
secured in position by means of the screw
33, it is to be understood that it may be other-
wise supported in operative relation with the
feed wheel 12 depending altogether upon the
115 particular type of support employed for the
feed wheel.

Operatively associated with the inner feed
wheel 13 and cooperating with the needle
guide 23 is a stitch finger supporting member
120 34 suitably positioned adjacent the upper
edge of the feed wheel. Supported upon this
member, by means of the screws 35, is the
stitch finger plate 36 terminating in the
stitch finger proper 37 of substantially nee-
125 dle-like form beneath which the needle 14 re-
ciprocates. This stitch finger 37 is of such
fine proportion that it is of material assis-
tance in the production of a seam of minimum
thickness or depth.

As most clearly appears in Figures 1 and 2, the supporting member 34 is flattened at its outer end for receiving the stitch finger plate 36 and is provided with an integral lug or projection 38 extending laterally over the edge of the feed wheel 13. The stitch finger plate is of substantially flat formation throughout, the outer edge thereof being provided with an integrally formed ear 39. The lug 38 on the supporting member 34 and the ear 39 on the stitch finger plate are arranged in superimposed relation with the lug 38 lying in the horizontal plane of the pressure member 27, such that the opposed edges of pressure member and lug are normally in contacting engagement. The ear 39 which overlies the lug 38 has its forward edge projecting to a slight extent over and beyond the meeting edges of the pressure member 27 and the lug 38, or, in other words, across the vertical plane of the path of movement of the fabric or material to be stitched.

As has already been stated it is essential in the production of a neat-appearing seam that the seam follow closely and accurately the longitudinally extending wale of the fabric. And in order to insure a seam of minimum thickness it is equally essential to take up as few wales as possible in the seaming operation, otherwise the seam will be too heavy. These desirable conditions are attained to considerable extent by virtue of the particular coaction and cooperation which is had between the spring pressed pressure member 27 and the lug 38 against which it abuts. The fabric to be seamed is fed through the machine in a substantially vertical plane with the upper edge thereof touching the under surface of the ear 39 of the stitch finger plate 36. This position of the fabric as it passes between the feed wheels is maintained by reason of the fact that the proximate edges of the member 27 and the lug 38 engage opposite sides of the fabric, the member 27 being constantly urged into firm engagement with the fabric by the action of the spring 28. The fabric-engaging edge of the lug 38 is curved to form with the curved fabric-engaging edge of the pressure member a flared opening 40 to permit smooth and uninterrupted entry of the fabric therebetween. The fabric, being thus fed between the feed wheels with the edges of the member 27 and lug 38 firmly engaging opposite surfaces thereof at all times, will be effectually prevented from dropping down and the needle 14 will as a result pass always between the same wales of the material. The seam will thus be perfectly straight and will be formed without any crossed wales. Further, due to the action of the spring-pressed pressure member 27 which constantly engages the fabric irrespective of variations in thickness thereof and so maintains the fabric in proper position at all times, it is possible to feed the fabric through the ma-

chine so that approximately only one, one and one-half or two wales in addition to each of the selvaged edges of the fabric are taken up in forming the seam.

Referring now to Figures 1, 3 and 4, it will be seen that there has been provided a fabric guiding and unfurling device, indicated generally as 41, which device cooperates with the pressure member and its associated parts in properly feeding and maintaining the fabric in stitching position. This device comprises essentially a suitably supported central bar 42 upon either side of which are pivotally supported, as at 43, a pair of uncurling plates or wings 44. A spring 45 is disposed between the upper ends of the plates 44, the action of this spring being such as to resiliently press the lower ends of the plates into engagement with the opposite sides of the fabric. Any suitable means may be employed for regulating the compressive force of the spring, and thumb-nuts 46 threaded upon a screw 47 and engaging opposite faces of the plates 44 may be provided for limiting the extent of movement of the lower ends of the plates toward one another. A pin 48, projecting across the plates 44 and through suitable openings 49 therein, serves as a lateral guide for the plates and also acts to limit the extent of upward movement of the fabric between the plates.

As appears most clearly in Figure 4, the plates 44 each terminate in fabric engaging portions, the inner or fabric engaging surfaces of which are provided with inclined serrations or grooves 51. These serrations cooperate with the feed wheels and the spring-pressed pressure member to feed the fabric through the machine with the upper edge thereof lying always in the same horizontal plane. By reason of the inclination given to the serrations, the tendency is for the fabric, as it is gripped by the plates 44, to ride upwardly into the flared opening 40 between the pressure member 27 and the lug 38, thus eliminating the possibility of its slipping downwardly from between the coacting faces of the guiding and unfurling plates. Obviously such an arrangement, insuring as it does the proper guiding and feeding of the fabric at all times, eliminates the necessity for the operator's constant attention at this point.

Figures 8, 9 and 10 show a modified form of fabric guiding and unfurling device in which the fabric engaging elements are mounted for substantially universal adjustment. In this arrangement the plates 55 are pivotally supported in a manner substantially similar to the plates 44 of the form shown in Figure 3. The inner faces of these plates below the pivot pins 43, however, are offset outwardly as at 56 and in the spaces formed by these offsets are located the relatively loosely mounted members 57, the inner faces of which engage the outer surfaces of the

105

110

115

120

125

130

fabric. These members 57 are substantially similar to the lower portions of the members 44 shown in Figures 3 and 4 and are preferably provided with the rearwardly and upwardly inclined serrations as in the former instance.

Both of the plates 55 are provided with openings 58. Screws 59, provided with enlarged heads 60, pass through the openings 58 and are threadedly received in the bodies 10 of the clamping members 57. The shanks of the screws are of smaller diameters than the openings 58 through which they pass thereby permitting considerable movement between the clamping members 57 and the plates 55 15 without, however, permitting their entire separation. In order to insure that the clamping members 57 bear evenly against the surfaces of the central member 42 (it being, of course, understood that one edge of the fabric passes 20 between this central member and one of the clamping members 57 and the other edge passes between the central member and the other clamping member 57) each of the clamping members is provided with a socket or recess 61 in its outer surface in which is received 25 a complementally formed projection 62 on the inner surface of each plate 55. These projections 62 may be formed integrally with the plates 55 or they may be in the form of ball 30 bearings, the important feature being the provision of a suitable fulcrum about which the clamping members may adjust themselves to compensate for variations in thicknesses 35 of the fabric. Obviously, an arrangement such as is shown in Figures 8, 9 and 10 insures the positive and uniform engagement of the sides of the fabric by the guiding and unfurling device as it passes therethrough 40 into the seaming mechanism.

It is to be understood, of course, that the spring pressed pressure member and the stitch finger plate which cooperates therewith may be mounted in any suitable manner 45 other than that disclosed herein. Also the fabric guiding and unfurling device may be mounted in any other suitable manner, it being only essential that the cooperating serrated plates 44 (Figure 4) or the plates 55 50 and their cooperating pressure members 57 (Figure 8) be so disposed with respect to the feed wheels and the stitching mechanism that the fabric to be stitched will be fed into the machine with its upper edge always moving 55 in the same horizontal plane. Other obvious and minor changes may be made from time to time in the details of construction and arrangement of parts without, however, departing from the spirit and principle of the 60 invention herein disclosed and accordingly it is desired that the same be claimed broadly, as well as specifically, as indicated in the appended claims.

What is claimed as new and useful is:

65 1. In a sewing machine, in combination, a

pair of oppositely rotatable feed cups adapted to feed a vertically arranged fabric through the machine, and a guiding and unfurling device disposed in the path of movement of said fabric, said device including a 70 pair of fabric engaging members, the fabric engaging surfaces of which are provided with complementally formed inclined grooves.

2. In a sewing machine, in combination, a 75 pair of oppositely rotatable feed cups adapted to feed a vertically arranged fabric through the machine, and a guiding and unfurling device disposed in the path of movement of said fabric, said device including a 80 pair of spring pressed members arranged to engage opposite sides of the fabric, the inner and fabric engaging faces of said members being provided with complementally formed grooves and ridges inclined with respect to 85 the horizontal.

3. In a sewing machine, in combination, a 90 pair of horizontally disposed fabric engaging members, said members being relatively movable to compensate for variations in thickness of the fabric, and a pair of vertically disposed fabric engaging members, the fabric engaging faces of which are each provided with a plurality of serrations inclined with respect to the horizontal for positively 95 guiding the fabric into proper position between said first mentioned fabric engaging members.

4. In a sewing machine, a fabric guiding 100 and unfurling device comprising a pair of spring-pressed pressure members, a fabric engaging member loosely mounted upon the inner surface of each of said pressure members, and means for insuring universal adjustment 105 of said fabric engaging members to compensate for variations in the thickness of the fabric.

5. In a sewing machine, a fabric guiding 110 and unfurling device comprising a pair of fabric engaging members, a pair of pressure members embracing said fabric engaging members and operative to press the latter into positive engagement with said fabric, and means permitting relative movement between said fabric engaging members and said 115 pressure members.

6. In a sewing machine, in combination, a 120 pair of horizontally disposed fabric engaging members, said members being relatively movable to compensate for variations in thickness of said fabric, and a pair of vertically disposed fabric engaging members, said latter members being serrated on their inner surfaces and being arranged for substantially 125 universal adjustment with respect to the vertical plane of movement of the fabric.

7. In a fabric unfurling device, a pair of spring-pressed pressure members, a fabric engaging member loosely supported by each of 130 said pressure members, and pressure equaliz-

ing means interposed between each fabric engaging member and its associated pressure member.

8. In a sewing machine, a fabric guiding and unfurling device, a relatively stationary separating member for maintaining the edges of a fabric in separated relation, a pair of fabric engaging members respectively operative to engage opposite faces of said separating member, a pair of spring-pressed pressure members carried by said separating member for actuating said fabric engaging members, and means permitting relative movement between each fabric engaging member and its coacting pressure member.

9. In a fabric guiding and unfurling device, a pair of fabric engaging members, a pair of spring-pressed pressure members respectively operative to actuate said fabric engaging members, and pressure equalizing means interposed between each fabric engaging member and its associated pressure member.

10. In a fabric guiding and unfurling device, a pair of fabric engaging members, a pair of spring-pressed pressure members respectively operative to actuate said fabric engaging members, and means interposed between each fabric engaging member and its associated pressure member for permitting relative movement therebetween.

Signed at Philadelphia, county of Philadelphia, State of Pennsylvania, this 29th day of March, 1927.

35 CARL FREDERICK MACK.
